UNITED STATES PATENT OFFICE.

WILLIAM C. ASHWELL, OF NEW YORK, N. Y.

WAGON-TOP.

SPECIFICATION forming part of Letters Patent No. 612,225, dated October 11, 1898.

Application filed June 6, 1898. Serial No. 682,677. (No model.)

To all whom it may concern:

Be it known that I, WILLIAM C. ASHWELL, a citizen of the United States, residing in New York city, in the county and State of New York, have invented a certain new and useful Improvement in Wagon-Tops, of which the following is a specification.

An umbrella, usually of large size, having the standard fixed to the wagon-body and affording limited shelter from the sun and rain has been long known and used. This invention belongs to that class, and has for its object increased protection from the weather when in place and facilities for easily removing and stowing it when not required.

It consists of an umbrella-like structure mounted upon a standard provided with a curtain attached to the edges and adapted to be detachably secured to the wagon-body and arranged to be pulled taut when the umbrella is fully distended and fastened. When thus strained, the several parts mutually strengthen each other, and the whole forms a stiff but light protecting-cover for the vehicle.

In the most approved form the umbrella portion is preferably rectangular in outline when in the open condition to match to the wagon-body, and means are provided for reliably holding the standard when in use and for folding it upon itself, and thus reducing the whole to small compass when out of service.

The invention also consists in certain details of construction and arrangement of parts to be hereinafter described.

The accompanying drawings form a part of this specification and show the manner in which I have carried out the invention.

Figure 1 is a side elevation of a light wagon equipped with my improved top. Fig. 2 is a plan or top view of the umbrella portion. The remaining figures are on a larger scale. Fig. 3 is a central longitudinal section through the wagon body and top, certain portions being shown in elevation. Figs. 4 and 5 are horizontal sections through the standard, taken, respectively, on the lines 4 4 and 5 5 in Fig. 3. Fig. 6 is a side view of the whole cover removed and folded.

Similar letters of reference indicate the same parts in all the figures.

A is the body of a light "run-about" wagon, and A' is the seat, having an opening a there-

in reinforced by the thimble A² and located directly above a squared socket A³, fixed to the floor of the body. In other respects the body and seat may be as usual and of any preferred style. The opening a and socket A³ receive the squared lower end B' of the standard B, made for convenience in two parts jointed together at b and held stiffly in line by the sleeve B², fitting snugly over the joint and supported by the pin b'. The standard supports an umbrella-top C, comprising the covering C', ribs C², braces C³, and slide C⁴, all of which may for the purposes of this description be of the ordinary or any approved materials and construction. I prefer that certain of the ribs be longer than others, as shown, so that when the umbrella portion is open or distended the outline shall be rectangular to conform to the body, as in Fig. 2; but this is not essential.

On the sides and rear edge of the umbrella is fastened a curtain D, which may be in one piece or of three or more parts joined at the angles of the wagon-body by straps D' or otherwise. The material should be a flexible waterproof fabric, and the lower edge is provided with eyes or buttonholes matching to and receiving the buttons or studs E, fixed on the body, thereby securing the curtain thereto.

The umbrella portion is held in the fully-open condition by the engagement of a spring-catch B⁵ below the slide C⁴, as usual, and B⁶ is a similar catch lower down on the standard serving to sustain the umbrella in a partially-distended condition.

In setting up the top the curtain D is unfolded or shaken out of the condition shown in Fig. 6 and the slide C⁴ released from the catch B⁵. The umbrella is then partly opened by moving the slide into engagement with the catch B⁶, and the standard is then straightened and secured by the sleeve B² and thrust through the opening a into the socket A³, the squared lower end B' aiding to hold the umbrella in position relatively to the body. In this slackened condition (shown in dotted lines in Fig. 3) the curtain is easily attached to the buttons E, and when so secured the slide C⁴ is thrust strongly upward, fully distending the umbrella and drawing the curtain smooth and taut and is held in this con-

dition by the upper catch B³. The top is removed and folded by reversing the operation, and it may then be carried in the wagon or otherwise conveniently stowed until needed.

5 The invention offers a light, strong, weather-proof top or cover easily set up and removed and occupying but little space when folded.

The stress imparted to the curtain when the umbrella is fully distended tends to stiffen 10 and strongly support the whole, and if the parts be properly proportioned the cover will successfully withstand any strains to which it is liable.

It is simple in construction, not expensive 15 to manufacture, and is neat and ornamental in appearance.

Modifications may be made in the forms and proportions within wide limits without departing from the principle of the invention 20 or sacrificing its advantages.

The materials employed may be varied and the invention applied to other styles of vehicles than that shown.

The curtain may be attached to the umbrella by buttons or other separable fastenings to allow the umbrella portion to serve alone as a protection from the sun. Additional curtains may be employed to close the front and forward portions of the sides, if desired, and openings suitably glazed may be provided, if necessary or desirable.

Instead of passing through the seat the standard may be supported in a bracket therefrom or in an independent holder. As shown, 35 the standard may pass between the seat-cushions when in use, and the opening in the seat will be concealed by their abutting edges when the top is out of use.

I claim—

40 1. In a wagon-top, an umbrella-like structure, comprising a foldable, jointed standard, ribs, braces, slide, and flexible covering, in

combination with two catches at different heights on the upper portion of the standard and arranged to hold the slide in position to 45 partially and to wholly distend the umbrella, and with curtains attached to the edges of the latter and to the wagon-body, all arranged to serve substantially as and for the purposes herein specified.

2. The standard B, B' jointed at b and having the sleeve B², the lateral pin projecting from the lower portion of the standard near the joint to support the sleeve, the ribs C², braces C³, covering C' and slide C⁴, in combination with the catches B³ and B⁴ at different heights on the upper portion of the standard and arranged to hold the ribs either wholly or 50 partially distended, and with the curtain D attached to the edges of said covering, and 55 means for attaching said curtain to a wagon-body, all arranged to serve with the latter substantially as and for the purposes herein specified.

3. The standard B having the lower portion B' squared and jointed thereto, in combination with the seat A' having the squared opening a, and the socket A³ adapted to receive said lower portion, and a socket A² on the under side of said seat, an umbrella-like 70 structure C supported by said standard, and the curtains D attached to the edges of said structure and to a wagon-body, and to be stretched taut when the structure C is in its uppermost position all adapted to serve with 75 the latter substantially as and for the purposes herein specified.

In testimony that I claim the invention above set forth I affix my signature in presence of two witnesses.

W. C. ASHWELL.
